UNITED STATES PATENT OFFICE.

JAMES F. HUGHES, OF YONKERS, NEW YORK.

GAME APPARATUS.

1,105,274.

Specification of Letters Patent. Patented July 28, 1914.

Application filed February 19, 1914. Serial No. 819,617.

To all whom it may concern:

Be it known that I, JAMES F. HUGHES, a citizen of the United States, residing at Yonkers, in the county of Westchester and State of New York, have invented certain new and useful Improvements in Game Apparatus, of which the following is a specification.

This invention is directed to the provision of apparatus for use in playing indoors a game similar in many respects to the game of golf.

The object of the invention is to provide apparatus with which a game may be played which is highly interesting for the players, which requires a high degree of skill, which affords ample opportunity for the exercise of judgment as to the best course to be pursued and which tends to increase materially the player's proficiency in that branch of the outdoor game of golf known as putting.

The invention involves the provision of a plurality of direction indicators and a putting plate which are adapted to be placed upon the playing surface, as for instance, a carpeted floor or other surface upon which the balls will roll in a manner similar to the rolling of a golf ball upon a green. The putting plate may be and preferably is of the general character shown in Patent 884,277, granted to me April 7, 1908. In combination with this, I employ a plurality of direction indicators which mark out a course doubling back and forth upon itself from the starting point to the putting plate. These direction indicators are specially constructed so as to provide a restricted space over which the player's ball must pass. Also, each of the direction indicators is made so as to permit it to be pivotally mounted. As a result of this, each player may turn any one of the direction indicators to such angular position as will permit him to play over or through it to the best advantage. In addition to these parts, I employ devices which I term "hazards" and which may be constructed in many respects like the direction indicators, particularly in that they include separated upright portions between which the ball may pass and in that they are arranged for pivotal mounting so that they may be turned to any angular position.

The preferred embodiment of the invention is illustrated in the accompanying drawings in which—

Figure 1 is a diagrammatic view of the apparatus, Fig. 2 is a plan view of one of the direction markers, Fig. 3 is a cross-section of the device shown in Fig. 2, Fig. 4 is a modified construction which may be employed instead of that shown in Fig. 2, and Fig. 5 shows one form of hazard.

The apparatus is usually employed for playing within a house. Fig. 1 indicates the carpeted floor of a room or the outline of a rug of substantial size. The starting point is indicated by markers placed near one corner of the room as shown at 5. From this starting point each player plays his ball over each of a plurality of direction indicators or markers 6, 7 and 8. From the last of these he plays the ball into a hole provided in a suitably shaped plate 9 which may be constructed in accordance with my patent above referred to.

The construction of each of the direction indicators or markers will now be described with reference to Figs. 2, 3 and 4. As shown in Figs. 2 and 3, each indicator consists of a disk 10 of thin sheet-metal, preferably of the same diameter as the hole on a golf course, namely, 4 $\frac{1}{4}$ ". At diametrically opposite points, upwardly extending standards 11 are provided on the disk 10, these standards forming uprights between which a ball must pass. Also, each disk 10 is centrally perforated as indicated at 12 so that it may be pivotally mounted by passing a tack through the central perforation 90 and into the carpet.

A modified construction which may be employed in lieu of that shown in Figs. 2 and 3 is indicated in Fig. 4. In this figure, the standards or uprights 13 are provided at 95 diametrically opposite points on the disk 14, but they are set in slightly from the periphery of disk 14 instead of being tangent to the disk. Encircling the disk is an annulus 15, the material of which is raised 100 slightly around the inner edge of the annulus as shown at 16. At a plurality of points around the inner edge of the annulus 15, tangs 17 are struck out from the metal of the annulus so that these tangs 105 and the edge portion 16 will lie on opposite

sides of the edge of disk 14. The disk 14 may thus be rotated within the annulus 15 to any desired annular position.

Referring again to Fig. 1, devices which I term "hazards" are shown at 18 and 19. These hazards are similar to the direction indicators or markers 6, 7 and 8, except for the construction of the uprights. The hazard 18 is shown as provided with uprights 10 which are V-shaped and arranged with the apices directed away from each other. The hazard 19 has the uprights 21 arranged in a plane diametrically of the base.

The player starting from the point 5 must play his ball over the marker 6 and between the uprights of that marker. If he fails to do so in his first shot, he may, on his next turn, again attempt to do so and in preparation for this second attempt, he may turn 15 this marker on its central pivot so that the diameter passing through the centers of the uprights is transverse to the direction of his shot. Having played over this first marker 6, he must then play over the marker 20 7, but before doing so, he must pass over the hazard 18 and between the uprights of that hazard. By reason of the angular arrangement of the uprights of this hazard 18, an 25 inaccuracy of the shot will cause the ball to be deflected laterally at a substantial angle. In like manner, the player must play his ball over the hazard 18, markers 7 and 8 and the hazard 19 and must then play it into the hole in the plate 9, a record being kept of 30 the total number of shots required by the player to hole out his ball in the manner indicated.

Another form of hazard which I may employ is shown at 22 in Fig. 1 and in detail in Fig. 5. This has a base 23 which is preferably of circular form and it is arranged to be pivoted by being centrally perforated at 24. On the base is mounted an upright wall 25 which is disposed substantially diametrically of the base and has its ends inclined slightly to one side of the general plane of the wall. The face of the base is provided with direction marks, preferably consisting of two arrows at right angles to each other and angles of about 45° to the wall 25. This hazard should be positioned close to the line of play, as the line from the starting point to the first direction indicator, and turned to such position that the wall 25 will serve to deflect a ball toward the center of the room. Fig. 1 shows this hazard so mounted. When so positioned, an inaccurate shot from the starting point will cause the ball to impinge upon the wall 25 45 and be deflected toward the center of the room and at a distance from the marker 6. To vary the condition of play, the hazard 22 may be changed in position upon the playing

surface from time to time and the arrows thereon facilitate returning the hazard to a 65 definite angular position if it were accidentally shifted.

Having described my invention, what I claim as new therein and desire to secure by Letters Patent of the United States is:

1. Golf game apparatus adapted to be placed upon the playing surface and comprising a base to rest upon the playing surface, two uprights projecting upwardly from the base and spaced apart to permit a 75 ball to pass between them and means for pivotally sustaining the uprights so that they may be turned to any angular position, substantially as set forth.

2. Golf game apparatus adapted to be placed upon the playing surface and comprising a base to rest on the playing surface and two uprights projecting upwardly from the base and spaced apart so that a ball may pass between them, said base being perforated to permit of pivoting it upon the playing surface so that it may be turned to any angular position, substantially as set forth.

3. Golf game apparatus comprising a thin metallic disk adapted to be placed upon the playing surface and two uprights extending upwardly from the base at diametrically opposite points, said uprights being spaced apart to permit a ball to pass between them and said disk being provided with centrally located means for pivoting it upon the playing surface so that it may be turned to any angular position, substantially as set forth.

4. Golf game apparatus adapted to be placed upon the playing surface and comprising a base to rest upon the playing surface, means located centrally upon the base for pivotally mounting the latter on the playing surface so that it may be turned to any angular position and an upright wall 105 extending across the base substantially diametrically and having its ends deflected laterally; substantially as set forth.

5. Golf game apparatus comprising a thin metallic disk adapted to be placed upon the playing surface and provided with centrally located means for pivoting it upon the playing surface so that it may be turned to any angular position and two uprights projecting upwardly from the base and spaced apart to permit a ball to pass between them, each of the uprights having the sides thereof inclined relatively to a diameter of the disk; substantially as set forth.

This specification signed and witnessed 120 this 18th day of February, 1914.

JAMES F. HUGHES.
